(57) **CLAIM**

The ornamental design for a light fixture, as shown and described.

DESCRIPTION

FIG. 1 is a front/left/top perspective view of a light fixture (a front/right/top perspective view would be a mirror image thereof);

FIG. 2 is a front/left/bottom perspective view thereof (a front/right/bottom perspective view would be a mirror image thereof);

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof; and,

FIG. 8 is a bottom plan view thereof.

The broken lines show portions of the light fixture that form no part of the claimed design, i.e., the portion of the wires and the ceiling box.
